METHOD AND APPARATUS FOR HANDLING
CONTINUOUS YARNS AND THE LIKEFrederick W. Koster, Wallingford, Pa., assignor
to American Viscose Corporation, Wilmington,
Del., a corporation of Delaware

Application April 17, 1945, Serial No. 588,835

7 Claims. (Cl. 242—1)

1

The present invention relates to methods and apparatus for the disposition or deposition of filamentary material of continuous nature, such as yarns, tows, cords, single continuous filaments, and the like.

For certain purposes, it is desirable to deposit continuous filamentary material in the form of over-lapping loops or coils. For example, a continuous yarn may be deposited in a series of loops which are made to over-lap by virtue of relative motion of the surface upon which the deposit is made during such time as the deposit is made. For example, yarns which need to be treated with fluids or liquids may advantageously be disposed on the upper surface of a continuously moving conveyor, especially of foraminous character, to present the yarn in an exposed and yet compact condition so that effective liquid treatment can be conveniently performed upon the yarn.

The primary object of the present invention is to provide a novel and efficient method and apparatus for depositing a continuous material, such as a yarn, in the form of a heaped coil upon a stationary surface or in the form of numerous staggered, partially over-lapping loops upon a continuously traveling surface. These and other objects of the invention are accomplished generally by a special method of utilizing a fluid yarn feeding and depositing stream. The stream preferably has a high velocity and travels in the direction it is desired to feed the yarn or other material where the material is first introduced into the stream so that by virtue of the suction produced at the point of entrance of material into the stream, the material is continuously drawn through the stream mainly by virtue of the flowing action of the stream. From the last portion of the channel, the stream is discharged into the atmosphere in a direction making an angle to that plane which contains the approximate direction of entrance of the strand into the stream and radiates from such direction to the position of discharge so that the discharge of the fluid stream causes rotation of the stream about the portion thereof which the material enters as an axis, the material being discharged by the stream in proximity to the receiving surface in an approximately circular pattern.

The single figure of the drawing discloses a simple form of apparatus embodying the invention, partially in cross-section, with the receiving surface shown in perspective as viewed from above.

Referring more particularly to the drawing, the

2

material 2 to be handled passes over a suitable guide, such as a roller 3, downwardly into the mouth 4 of the depositing device which comprises an outer housing 5 within which there is rotatably mounted, as on a bearing 6 of anti-friction type preferably, an annular block 7 into the bore of which, the mouth piece 8 extends partially. A suitable annular seal 9 may be provided to prevent excessive leakage of the fluid past the bearing. The fluid may be introduced by the connection 10 and flows into the bore through the annular block 7 in the direction of travel of the entering material as controlled by the flaring mouthpiece 8. The block 7 has a tube 11 depending therefrom. The tube communicates with the bore within the block 7 and has a bend at 12 and a second bend at 13. The terminal portion of the tube from the bend 13 has a discharge opening 14 and extends at an angle to the axis of the bore of the block 7 and at an angle to any line radiating from such axis to the terminal portion so that discharge of the fluid repels the tube in a direction away from the discharge opening 14. Such repulsion causes rotation of the tube and the block as a unit so that the material discharged from the tube onto the receiving surface 15, such as a belt, takes the form of approximately a circle. Thus, as long as a fluid medium is introduced through the connection 10, the material 2 will be drawn into the device and forced through the tube which is continuously rotated by the effect of the portion of the fluid stream being discharged with the filamentary material through the exit 14.

35 While the receiving surface is shown in the drawing as a continuously traveling belt which may conduct the deposited material through liquid treatment stages, it may instead take the form of an annular rim portion of a rotating wheel or disk, which shortly after depositing of the material thereon passes under liquid or fluid treatment sprays or the like. The material, after treatment, may be withdrawn from the receiving surface in any suitable manner.

40 The filamentary material may proceed from any suitable source, such as a wound package of the material to be treated. Alternatively, it may proceed directly from an artificial fiber or filament spinning machine either as a single continuous filament or as a bundle of a multiplicity of such filaments either twisted or untwisted. For example, the invention is particularly useful for the disposition of yarns of regenerated cellulose, cellulose derivatives, casein or other proteins, polymers, copolymers, and condensation

products, such as vinyl resins and the nylons. The material to be treated may of course be composed of natural fibers, such as yarns of cotton, wool, silk, and the like. Strands of material not necessarily of textile character, such as ropes, cables and wires may also be handled by the present invention provided they are sufficiently flexible.

The method of the present invention, involving as it does the use of a fluid medium for conveying the material has the advantage of producing a negligible abrasive effect upon the material. Slight twisting is also effected but this is removed when the coils are withdrawn from the receiving surface. The fluid for the conveying stream may suitably be air or other gas. Alternatively, it may be steam or other vapor or a mixture of air and steam or it may yet be constituted of a liquid with which it is desired to treat the material simultaneously with its deposition. In such case suitable side walls may advantageously be provided adjacent the receiving surface where the material is being deposited to control the spray of liquid.

It is to be understood that changes and variations may be made in the invention without departing from the spirit and scope thereof as defined in the appended claims.

I claim:

1. The method of depositing a strand of substantially continuous length comprising conveying it in a laterally enclosed fluid stream, and discharging, above a receiving surface, the fluid with the material at an angle to that plane which contains the approximate direction of entrance of the strand into the stream and radiates from such direction to the position of discharge so that the strand discharge portion of the stream rotates about a portion thereof adjacent the strand entrance, thereby laying the strand on the surface in coiled form.

2. The method of depositing a strand of substantially continuous length comprising conveying it in a laterally enclosed fluid stream and discharging, above a moving receiving surface, the fluid with the material at an angle to that plane which contains the approximate direction of entrance of the strand into the stream and radiates from such direction to the position of discharge so that the strand discharge portion of the stream rotates about a portion thereof adjacent the strand entrance thereby laying it on the surface in coiled form with partially overlapped loops.

3. Apparatus for handling a strand of substantially continuous length comprising a rotatable channel having a strand entrance in approximate alignment with the axis of rotation and a strand discharge portion offset from its strand entrance, the discharge portion being arranged to extend at an angle to all planes which contain the axis of rotation and radiate therefrom to the discharge portion, and means for forcing a fluid stream through the channel toward the strand discharge thereof.

4. Apparatus for handling a strand of substantially continuous length comprising a rotatable

channel having a strand entrance in approximate alignment with the axis of rotation and a strand discharge portion offset from its strand entrance, the discharge portion being arranged to extend at an angle to all planes which contain the axis of rotation and radiate therefrom to the discharge portion, and means for forcing a fluid stream through the channel toward the strand discharge thereof, and a receiving surface disposed below the strand discharge portion of the channel.

5. Apparatus for handling a strand of substantially continuous length comprising a rotatable channel having a strand entrance in approximate alignment with the axis of rotation and a strand discharge portion offset from its strand entrance, the discharge portion being arranged to extend at an angle to all planes which contain the axis of rotation and radiate therefrom to the discharge portion, and means for forcing a fluid stream through the channel toward the strand discharge thereof, a receiving surface disposed below the strand discharge portion of the channel and means for moving the receiving surface in a direction transversely of the axis of rotation of the channel.

6. Apparatus for handling a strand of substantially continuous length comprising a rotatable channel having a strand entrance in approximate alignment with the axis of rotation and a strand discharge portion offset from its strand entrance, the discharge portion being arranged to extend at an angle to all planes which contain the axis of rotation and radiate therefrom to the discharge portion, and means comprising an annular passage about the strand entrance for directing a fluid stream through the channel toward the strand discharge thereof whereby the stream creates suction in the strand entrance for drawing the strand into the channel.

7. Apparatus for handling a strand of substantially continuous length comprising a housing having apertures in its end walls, a member rotatably mounted in the housing and having an axial bore concentrically disposed with respect to the apertures, an annular element projecting from one of the apertures partially into the adjacent end of the bore of said member, a tube secured to the member with its channel communicating with the axial bore, said tube having an intermediate portion thereof extending at an angle to the bore and having an open-ended terminal portion extending at an angle to all planes which contain the axis of the bore and radiate therefrom to the discharge portion, and means whereby a fluid can be supplied to the interior of the housing.
